CAP

Theron W. Johnson, Bay Pines, Fla.

Application January 7, 1943, Serial No. 471,597

9 Claims. (Cl. 2—195)

This invention relates to cloth caps.

An object of this invention is to provide an improved cap which can be formed from a single blank piece of cloth.

Another object of this invention is to provide a cap which is designed for the armed forces, either military, naval, air or other branches of the service, and which will retain its shape more readily than the caps now in use.

A further object of this invention is to provide a cap which has the general appearance of caps at present in use, but which can be constructed at a material saving in time, labor and material.

A further object of this invention is to provide a cap of this kind which can be worn inside a helmet, and can be adapted for use in different climates without change in construction.

A further object of this invention is to provide a cap of this kind which is an all-purpose cap for the armed forces and can be folded into a small compact package for placement inside a helmet when not in use.

A further object of this invention is to provide an improved method of constructing a cloth cap which will eliminate unnecessary labor and reduce waste to a minimum.

To the above objects and to others which may hereinafter appear, the invention consists of the novel construction, combination and arrangement of parts as will be more specifically described and illustrated in the accompanying drawings, wherein is shown an embodiment of the invention, but it is to be understood that changes, variations and modifications may be resorted to which fall within the scope of the invention, as claimed.

In the drawings:

Figure 1 is a detail side elevation of a cloth cap constructed according to an embodiment of this invention;

Figure 2 is a detail front elevation of the cap;

Figure 3 is a detail side elevation of the cap with the rim turned down;

Figure 4 is a fragmentary sectional view, taken on the line 4—4 of Figure 3;

Figure 5 is a detail side elevation of the cap turned inside out;

Figure 6 is a fragmentary side elevation of a modified form of ear muff construction attached to the rim;

Figure 7 is a plan view of the blank from which the cap is made and showing the initial steps in forming the cap;

Figure 7a is a fragmentary sectional view taken on the line 7a—7a of Figure 7;

Figure 7b is a fragmentary sectional view taken on the line 7b—7b of Figure 7;

Figure 8 is a view, similar to Figure 7, but showing the second step in the construction of the cap;

Figure 9 is a detail side elevation of a further step in the construction of the cap; and

Figures 10 to 13 inclusive show additional successive steps in the construction of the cap.

Referring to the drawings and first to Figures 7 to 13 inclusive, the numeral 15 designates generally the crown portion of the cap and the numeral 16 designates generally the rim portion of the cap. The crown portion 15, as shown in Figure 7, is initially formed of substantially frustro-triangular configuration being provided with upwardly convergent opposite end portions 17, and a truncated top portion 18. The rim 16 is constructed integrally with the base of the crown portion 15, and comprises a rim body 19 and wing members 20 at the opposite ends of the body 19 which project beyond the inclined ends 17 of the crown 15.

The wings 20 have an arcuate outer edge 21 and a straight inner edge 22.

The first step of the formation of the cap after the cloth has been cut to the pattern or configuration shown in Figure 7 is to fold the top edge 18 inwardly and then stitch, as at 23, along a line parallel with the top edge 18. The stitching 23 forms a bead 24 which is adapted to extend from the front to the rear of the completed cap. That portion 25, projecting beyond the bead 24, provides a pleat, as will be hereinafter described.

The outer edge of the rim member 16 is folded inwardly, as at 26, and a braid 27 is then stitched by a double row of stitching 28 to the folded portion 26.

The next step in the construction of the cap is to fold the crown 15 over the rim 16 along the line 29. The overlying crown 15 is then stitched to the adjacent edge of the rim 16 by pairs of upwardly convergent lines of stitching 30 and 31. The unstitched portion 32, between the convergent ends of the stitchings 30 and 31, constitute a bellows or distortable crown portion which will permit the shaping of the cap to the configuration of the head.

After the stitchings 30 and 31 have been made, the crown 15 and the rim 16 are cut, as indicated at 33, on a line co-planar with the edge 22 of the wing 20. The cuts 33 terminate at their inner ends closely adjacent the outer or lower ends of the outermost stitchings 30 and 31. The crown 15 is then folded back to its original position and

the entire piece of material is then folded upon itself with the two wings 20 overlapping each other. The crown 15 then has the upper and end edges thereof stitched together by stitchings 34, 35 and 36. The stitching 36 goes through the folded edge portion of the crown 15 whereas the stitching 34 goes through the opposite ends 17 of the crown. The stitching 35, which is a continuation of the two stitchings 34 and 36, goes through the material at a point outwardly of the stitching 23. The space 37 between the stitching 35 and the bead 24, forms a pleat 38 which extends from front to rear of the top of the crown 15. The flaps 39, which are formed by the cuts 33, are then stitched by a line of stitching 40, to the adjacent end of the crown 15. The wings 20 are now brought together in overlapping position and are stitched to the inner portion of the rim 16 by a line of stitching 41. The line of stitching 41 is placed at a point where it will underlie the sweat band 42 which is stitched to the lower end of the crown 15 by stitchings 43 and 44.

The sweat band 42 is adapted to overlie the ends 25 of the wings 20 as shown more clearly in Figure 5. The sweat band 42 is preferably secured to the lower end of the crown 15 on a longitudinally curved line, as shown at 45 in Figure 7, so that when the cap is in applied position the sweat band will be in a straight line on the head. After the sweat band 42 has been stitched to the cap the front and rear ends of the cap are stitched together by stitchings 46 and 47 respectively, which extend through the right side of the cap and form flattened front and rear portions which serve to stiffen the peaks formed by the front and rear of the cap.

The cap may be provided with a visor which, under normal conditions, may be hidden beneath the rim 16. The visor, generally designated as 48, is constructed in the form of a flexible piece of material 49 which is cut to the desired configuration and is then stitched as by stitching 50 to the adjacent or inner edge of the rim 16. The material 49 is then folded upon itself and stiffening material inserted between the folded sides of the material 49 whereupon the free edges of the material 49 are stitched together, as by stitching 51. In the normal wearing of the cap the visor 48 will be reverted from the position shown in Figure 13, extending upwardly and forming a stiffening element for the rear peak of the cap.

When it is desired to use the cap with the visor, the cap is turned from front to rear and also turned inside out thereby positioning the visor 48 on the inner or lower side of the rim 16. The visor 48, in this position, serves to hold the rim of the cap outwardly and away from the forehead of the wearer.

The cap, as shown in Figures 3 and 4, may be provided with ear muffs and for this purpose the rim 16 has stitched to one side thereof, and preferably to the inner side, a rectangular piece of material 52 which is stitched as at 53 and 54 to the rim 16. The opposite ends of the muff cover 52 are open and a suitable padding 55 may be inserted between the cover 52 and the adjacent face of the rim 16. The cover 52 constitutes a pocket which is open at each end to permit the insertion or removal of the padding 55.

In Figure 6 there is disclosed a slightly modified form of ear muff construction wherein a pair of narrow straps 56 are stitched to the inner side of the rim 16, and an ear muff element 57, which may be in the form of tufted material or a small

piece of fur, is removably secured to the inner side of the straps 56 by snap fastener members 58. When the cap is reversed to position the ear muff members 57 in confronting position to the ears, the muff members 57 will contact directly with the ears whereas in the construction shown in Figure 4 the wall 52 of the pocket will contact with the ear.

The cap hereinbefore described will permit the construction of the cap out of a single piece of material thereby effecting a material saving in material and also in labor, these two items affecting the cost of the cap. A cap constructed according to this invention will have upwardly projecting peaks at the front and rear thereof, above the rim 16, and the provision of the bellows portion 32 will permit more closely shaping of the cap to the head than is possible in caps of similar construction at present available.

This cap will, in worn position, have substantially a straight line from front to rear at the upper ends of the front and rear peaks and the front and rear ends of the caps will extend upwardly in a divergent position from the front to the rear of the head of the wearer. This construction will permit a more uniform configuration of the cap on different heads than is possible with caps at present in use, and this cap can readily be formed into a small package and positioned within a helmet or other article.

What I claim is:

1. A cap comprising an expandible crown formed of a single piece of elongated material folded upon itself and stitched together along the front, rear and through the longitudinal center, a rim integral with said crown and foldable to a position encompassing the lower portion of said crown, and short lengths of stitching extending through the front and rear portions of said crown, said short lengths of stitching providing stiffening means at the front and rear of the crown.

2. A cap comprising a crown formed of a single piece of elongated material having a truncated triangular configuration, said crown including opposed pairs of folded spaced apart portions, opposed pairs of upwardly convergent stitchings extending through said folded portions, the space between the inner convergent ends of said stitchings providing an expandible crown portion, and a reversible rim integral with the lower edge of said crown.

3. A cap comprising a crown formed of a single piece of elongated material having a truncated triangular configuration, said crown including opposed pairs of folded spaced apart portions, opposed pairs of upwardly convergent stitchings extending through said folded portions, the space between the inner convergent ends of said stitchings providing an expandible crown portion, a reversible rim integral with the lower edge of said crown, and ear muffs carried by one side of said rim.

4. A cap comprising a crown formed of a single piece of elongated material having a truncated triangular configuration, said crown including opposed pairs of folded spaced apart portions, opposed pairs of upwardly convergent stitchings extending through said folded portions, the space between the inner convergent ends of said stitchings providing an expandible crown portion, a reversible rim integral with the lower edge of said crown, and a flexible visor secured to the inner portion of said rim and concealable between the rim and the crown.

5. A cap comprising a crown formed of a single piece of elongated material having a truncated triangular configuration, said crown including opposed pairs of folded spaced apart portions, opposed pairs of upwardly convergent stitchings extending through said folded portions, the space between the inner convergent ends of said stitchings providing an expandible crown portion, a pair of pocket forming members secured to one side of said rim, and ear muff elements engaging between said rim in said pocket forming members.

6. A cap comprising a crown formed of a single piece of elongated material having a truncated triangular configuration, said crown including opposed pairs of folded spaced apart portions, opposed pairs of upwardly convergent stitchings extending through said folded portions, the space between the inner convergent ends of said stitchings providing an expandible crown portion, a reversible rim integral with the lower edge of said crown, pairs of straps secured to one side of said rim, an ear muff member engaging between a pair of said straps and said rim, and releasable holding means for said ear muff member.

7. A cap comprising a crown formed of a single piece of elongated material having a truncated triangular configuration, said crown including opposed pairs of folded spaced apart portions, opposed pairs of upwardly convergent stitchings extending through said folded portions, the space

between the inner convergent ends of said stitchings providing an expandible crown portion, a reversible rim integral with the lower edge of said crown, ear muffs carried by one side of said rim, and a flexible visor secured to the inner portion of said rim and concealable between the rim and the crown.

8. A cap comprising a crown formed of a single piece of material, a rim integral with said crown, said crown folded upon itself and stitched together by vertical extending front and rear lines of stitching, a longitudinal stitching extending across the top of the crown and connecting said front and rear stitchings, and plait forming means carried by said crown inwardly of and parallel with said longitudinal stitching.

9. A cap comprising a crown formed of a single piece of material, a rim integral with said crown, said crown folded upon itself and stitched together by vertical extending front and rear lines of stitching, a longitudinal stitching extending across the top of the crown and connecting said front and rear stitchings, plait forming means carried by said crown inwardly of and parallel with said longitudinal stitching, and opposed pairs of stitchings through said crown inwardly of said first stitchings, the members of each pair of stitchings being spaced apart at their inner ends to thereby provide an intermediate expandible portion.

THERON W. JOHNSON.
